UNITED STATES PATENT OFFICE.

WILLIAM H. DOANE, OF CINCINNATI, OHIO.

DESIGN FOR A TENONING-MACHINE.

SPECIFICATION forming part of Design No. 12,949, dated May 23, 1882.

Application filed September 29, 1881. Term of patent 7 years.

To all whom it may concern:

Be it known that I, WILLIAM H. DOANE, a citizen of the United States, residing at Cincinnati, in the county of Hamilton and State of Ohio, have invented and produced a new and useful Design for Tenoning-Machines, of which the following is a specification, reference being had to the accompanying drawings, forming part thereof.

10 A tenoning-machine embodying my design is represented in perspective in the accompanying drawings, which is deemed sufficient for the illustration thereof.

15 The leading feature of my design consists in so constructing the vertical frame or column at the front of which the cutting-tools are mounted as to leave a deep gap therein between and extending rearwardly from said cutters, the lumber-carrying stand extending laterally from one side of the column and opposite site and in line with the gap therein.

20 Figure 1 is a perspective view, giving the general outlines of the machine, including the cutter-heads and other parts. Fig. 2 is a perspective view, illustrating more clearly the configuration of the frame.

25 A is the vertical frame or column, the upper part of which terminates in a goose-neck, A', thus leaving a deep gap in said column. The 30 end of the goose-neck is provided with a head, B, having bearings in which is mounted a shaft, C, carrying on its right-hand overhung

end a cutter-head, and on the front of the column, below the gap, is also a head, B', provided with a similar shaft, C', and cutter-head. The 35 heads B and B' are arranged vertically with relation to each other. A cutter-head, D, is mounted on a vertical shaft at the right-hand side of the column. The position of this cutter-head is about midway of the height and 40 depth of the gap. The lumber-supporting stand E is placed a little distance from the right-hand side of the column, and extends laterally from said column in a line parallel with the front thereof.

45 I have illustrated and described the cutter-heads merely for the purpose of showing the general appearance of the machine.

I claim—

50 The design for a tenoning-machine herein shown and described, the same consisting of a column for supporting the cutting mechanism and terminating with a goose-neck, so as to exhibit a deep rearwardly-extending gap, and a stand extending laterally from one side 55 of the column for supporting a lumber-carriage opposite the gap in said column.

In testimony whereof I affix my signature in the presence of two witnesses.

W. H. DOANE.
